BOTTLE CRATE

Henry V. Bowman, Minneapolis, Minn., assignor
to Bowman Products, Incorporated, St. Paul,
Minn., a corporation of Minnesota

Application May 14, 1934, Serial No. 725,500

13 Claims. (Cl. 217—19)

This invention relates to new and useful improvements in bottle crates, generally, and more particularly to milk bottle crates.

Heretofore, it has been common practice in the manufacture of bottle crates to provide metallic partitions therein, either in the form of rods or metal stampings, to separate the bottles from one another and thus prevent direct contact therebetween. To use metal for this purpose has been found objectionable for several reasons. First, the metal has a tendency to mar the walls of the bottles as a result of the latter contacting therewith, often to the extent that small scratches or marks are made in the surface of the glass, which often cannot be removed. These scratches accumulate dirt and other foreign matter and thus render the bottles very difficult to clean. Secondly, these metallic partitions are usually galvanized or otherwise treated to prevent rusting. This protecting coating or galvanizing often wears off, whereupon the metal rusts. This rust is transmitted to the walls of the bottles in the form of a stain, which is usually very difficult to remove. Further, when metallic partitions are used, the crates are noisy, particularly when the bottles are empty, and the crates are being transported on a truck or other transporting means over a rough street surface. Conventional crates, such as above described, are also rather difficult to clean because of the longitudinal and transverse partitions provided therein, which usually extend from end wall to end wall, and side wall to side wall, whereby a brush or other cleaning instrument cannot be passed freely from end to end or crosswise of the crate.

In the novel crate herein disclosed, all of the objectionable features above enumerated have been eliminated, whereby a crate is provided which does not mar or stain the walls of the bottles, and is very easy and simple to clean, and may therefore be readily maintained in a sanitary condition. The means for spacing apart the bottles in the crate is such that the crate is rendered practically noiseless, even when filled with empty bottles and transported on a truck over a rough road or street.

The primary object of the invention, therefore, is to provide a bottle crate in which substantially all of the objectionable features now commonly present in conventional crates, have been eliminated, which is very simple and inexpensive in construction, and in which the walls of the bottles are cushioned to eliminate

noise and bottle breakage, even though the crate is subjected to treatment in transit, as is often the case with devices of this character.

Other objects of the invention reside in the particular construction of the bottle spacing means or elements, which are constructed of resilient or yieldable material such, for example, as rubber, whereby they cannot mar or injure the surfaces of the walls of the bottles, and whereby the bottles are cushioned; in the novel means provided for supporting the bottle spacing elements in the lower portion of the crate; in the novel construction of the upper portions of said bottle spacing elements which cooperate to substantially fill the spaces between adjacent bottles and thus provide ice ledges or shelves for supporting chipped or cracked ice, which is desirable when transporting bottled milk in crates during warm weather; and, in the simple and inexpensive construction of the spacing elements and the manner of securing them in position in the crate.

Other objects of the invention will appear from the following description and accompanying drawings and will be pointed out in the annexed claims.

In the accompanying drawings there has been disclosed a structure designed to carry out the various objects of the invention, but it is to be understood that the invention is not confined to the exact features shown as various changes may be made within the scope of the claims which follow.

In the drawings:

Figure 1 is a plan view showing a crate employing my invention;

Figure 2 is a cross-sectional view on the line 2—2 of Figure 1, showing one method of securing the tubular bottle spacing elements in position in the crate;

Figure 3 is a perspective view showing one of the tubular bottle spacing elements removed from its supporting means;

Figure 4 is a view showing another construction in which the bottle spacing elements are supported upon a metal plate which, in turn, is secured in position between the walls of the crate;

Figure 5 is a detail sectional view on the line 5—5 of Figure 4, showing the means for securing the tubular elements to the bottom plate; and

Figure 6 is a view showing still another method of securing the tubular bottle spacing elements to the bottom plate.

In the selected embodiment of the invention here shown, there is illustrated in Figure 1, for purposes of disclosure, a milk bottle crate comprising end walls 2 and side walls 3, preferably constructed of slats suitably secured together at the corners of the crate by suitable metallic corner irons 4, which is more or less common in structures of this kind.

To support the bottles within the crate, a plurality of spaced rods 5 are provided in the lower portion of the crate and are shown having their terminals or end portions suitably secured to the lower slats 6 of the end walls 2 of the crate. The bottles 7, indicated in broken lines in Figure 2, may be supported directly upon the rods 5.

Suitable transverse hangers or members, generally indicated by the numeral 8, are disposed transversely of the crate and have apertures 9 therein for receiving the rods 5, as clearly shown in Figure 2. The end portions 9 of the cross members 8 are preferably shaped as shown in Figure 2, whereby they may be engaged with the upper edges of the lower slats 11 of the side walls 3 of the crate walls, to thereby support the hangers or members 8 in the position shown in Figure 2. The outwardly bent flanges 12 of the end portions 9 are provided with suitable apertures 13 adapted to receive pins 14, received in suitable sockets 15 provided in the upper edges of the lower slats 11 of the side walls 3, as clearly shown at the right hand side of Figure 2. The pins 14 are retained in the sockets 15 by the adjacent slats 16 of the side walls, as will readily be understood.

An important feature of the invention resides in the construction of the novel means provided in the lower portion of the crate for spacing apart the bottles supported therein, to thereby prevent them from directly contacting with one another. As shown, in Figures 2 and 3, such means resides in the provision of a plurality of hollow elements, generally indicated by the numeral 17. These elements are preferably tubular in cross-section, and are made from a yieldable or resilient material such, for example, as rubber.

In Figures 2 and 3, each element 17 is shown shaped with downwardly extending legs 18 adapted to fit over the enlarged portions 19 of the cross members 8. Each enlarged portion 19 is shown provided with a raised cylindrical portion 21 forming a seat for the body of the element 17 to thereby prevent the lower portions of the walls thereof from collapsing, when pressure is applied to the outer surfaces thereof, as will be clearly understood by reference to Figure 2. The depending legs 18 of the members 17 engage opposite sides of the enlarged portions 19 and are secured thereto by such means as rivets or bolts 22.

A suitable cap, generally indicated by the numeral 23 is provided at the upper end of each tubular element 17. These caps are shown in Figures 1 and 2, and have cylindrical portions 24 fitting into the upper ends of the elements 17, and are suitably secured to their respective elements, by such means as vulcanizing, it being understood that the caps 23 are preferably made of hard rubber. Each cap 23 is preferably provided with a plurality of radial arms 25, shaped as shown in Figure 1, and adapted to extend outwardly into the spaces between the bottles, as shown, and cooperate to provide ice ledges or

shelves for supporting cracked or chipped ice between the bottles. The walls 26 between the arms 25 may be arcuately formed, as shown in Figure 1, to thereby substantially fit the peripheries of the bottles.

In Figures 4 and 5, there is shown another construction in which the bottom of the crate consists of a plate 27, shown bounded by a downwardly turned flange 28 adapted to be seated against the lower slats 29 and 31 of the end and side walls of the crate, respectively. These flanges may be secured to the bottom slats of the crate by suitable means such as rivets, not shown in the drawings.

A plurality of raised cylindrical portions or bosses 32 are provided in the bottom plate 27, each adapted to receive a tubular element 33 of flexible material such as rubber. The tubular elements 33 may be secured to the raised portions or bosses 32 by such means as rivets 34.

In the form shown in Figures 4 and 5, each tubular element 33 is provided with a cap 35, which is substantially circular to conform to the shape of the elements 33, as clearly illustrated in Figure 4. The flexible elements 33 are spaced apart as clearly illustrated in Figure 4 to thereby provide spacers for the bottles 7, indicated by the dotted lines, whereby said bottles cannot contact directly with one another. Suitable openings 36 are shown provided in the bottom plate 27, whereby water may be freely circulated through the crate for cleaning purposes.

Figure 6 illustrates another construction in which the raised portions or bosses 37 are not integrally formed with the bottom plate 27, but are independently formed and secured thereto by suitable means, not shown, such as electric spot welding or riveting. Each raised portion or boss 37 is shown provided with a flange 38 adapted to be seated, preferably against the bottom face of the plate 27, as clearly illustrated. Suitable apertures are, of course, provided in the plate to receive the bosses 37, as shown.

In the form here shown, the flexible elements 39 are secured to the bottom plate 27 by means of a bolt 41, having its upper end received in an aperture provided in the cap 42 and its lower end received in an aperture provided in the raised portion or boss 37. The bolt has an enlarged head 43 seated against the upper end of the cap 42 and is provided at its lower end with a nut 44, whereby the bolt may be tightened to securely clamp the element 39 and cap 42 to the bottom plate 27. When thus constructed, the raised portions or bosses 37 need not necessarily be riveted or secured directly to the bottom plate 27, as it will readily be noted by reference to Figure 6, that when the nut 44 of the bolt 41 is tightened, a portion of the bottom plate 27 will be clamped between the lower end of the tubular element 39 and the flange 38, whereby said parts are securely clamped to the bottom plate.

The novel means herein disclosed for spacing apart the bottles in the crate has been found very practical and desirable in actual operation for the reason that it provides a milk crate which may be roughly handled without noise and also, whereby the bottles are not likely to become broken. Because of the spacing elements 17, 33, and 39 being made from a flexible material such as rubber, the outer surfaces of the bottles are not marred or damaged, as is now a common occurrence when using spacing means or separators constructed entirely of metal. The spacing means is also very simple and inex-

5 pensive in construction, and because of each element 17 being constructed independently of the other elements of the same crate, they may readily be removed for repairs, or another element substituted therefor, without disturbing the remaining elements.

10 Another important feature of the invention resides in the fact that the spacing means provided in the crate are in the form of individual elements or units which are disconnected from one another, whereby a brush may readily be passed between said elements for cleaning purposes, which is impossible in the usual form of spacing means now commonly provided in milk 15 bottle crates, and the like.

I claim as my invention:

1. A bottle crate comprising side and end walls, a perforated bottom supported by said walls, and a plurality of flexible elements 20 formed of yieldable material that is bendable in any direction secured to said bottom in spaced relation and extending upwardly into the crate and cooperating to space apart the bottles to prevent direct contact therebetween.

25 2. A bottle crate comprising a plurality of walls, means in the lower portion thereof for supporting the bottles, and a plurality of unconnected, flexible, elements formed of yieldable material that is bendable in any direction 30 for spacing apart said bottles to prevent direct contact therebetween.

3. A bottle crate comprising a plurality of walls, means in the lower portion thereof for supporting the bottles, and a grid structure for 35 spacing apart said bottles to prevent direct contact therebetween, said grid structure being constructed entirely of rubber.

4. A bottle crate comprising a plurality of walls, means in the lower portion of said crate 40 for supporting the bottles, a plurality of tubular flexible elements on said means for spacing apart said bottles to prevent direct contact therebetween, and a head at the upper end of each of said elements having radial arms extending between the bottles and cooperating to provide ice ledges.

5. A bottle crate comprising a plurality of walls, means in the lower portion of said crate 50 for supporting the bottles comprising a plurality of cross members, and a plurality of flexible elements formed of yieldable material that is bendable in any direction secured to said cross members and spacing apart said bottles to prevent direct contact therebetween.

55 6. A bottle crate comprising a plurality of walls, a plurality of cross members in the lower portion of the crate cooperating to provide supports for the bottles, and a plurality of tubular rubber elements secured to said cross members 60 and spacing apart said bottles to prevent direct contact therebetween, said elements being capable of returning to their normal shapes, when distorted or bent out of shape.

7. A bottle crate comprising a plurality of 65 walls, bottle supporting means in the lower portion of the crate, and upright tubular flexible rubber elements secured to said bottle supporting means and spacing apart the bottles in the crate to prevent direct contact therebetween.

8. A bottle crate comprising a plurality of walls, a series of rods in the lower portion of the crate upon which the bottles are supported, cross members engaged with said rods, and a plurality of resilient tubular elements secured to said cross members and extending upwardly therefrom and cooperating to space apart the bottles to prevent direct contact therebetween.

9. A bottle crate comprising a plurality of walls, a series of rods in the lower portion of the crate upon which the bottles are supported, cross members engaged with said rods and secured to opposite walls of the crate, a plurality of resilient tubular elements secured to said cross members and extending upwardly therefrom and cooperating to space apart the bottles to prevent direct contact therebetween, and means on the upper portions of said tubular elements for supporting cracked ice between the bottles.

10 10. A bottle crate comprising a plurality of walls, a series of rods in the lower portion of the crate having their ends suitably secured to the end walls thereof, a plurality of cross members engaged with said rods and arranged 25 at substantially right angles thereto and having their ends suitably secured to the side walls of the crate, a plurality of resilient cylindrical elements secured to said cross members and cooperating to provide spacers for the bottles 30 to prevent direct contact therebetween, and means for preventing said cylindrical elements from collapsing, when engaged by an obstruction.

11. A bottle crate comprising a plurality of 35 walls, a series of rods in the lower portion of the crate having their ends suitably secured to the end walls thereof, a plurality of cross members engaged with said rods and arranged at substantially right angles thereto and cooperating therewith to provide a bottom for the crate, a plurality of resilient hollow elements secured to said cross members and cooperating to provide spacers for the bottles to prevent direct contact therebetween, and a plurality 45 of radial arms at the upper ends of said elements projecting between the bottles and cooperating to provide ice-supporting shelves.

12. A bottle crate comprising side and end walls, a perforated metallic bottom supported 50 by said walls and having raised portions integrally formed therein, and a plurality of flexible, hollow elements bendable in any direction fitting over said raised portions and extending upwardly into the crate and cooperating to space 55 apart the bottles supported in the crate.

13. A bottle crate comprising side and end walls, a bottom secured to said walls and having a series of openings therein spaced equidistant apart, cup-shaped elements inserted in said 60 openings and projecting above the upper surface of the bottom to provide, in effect, a series of cylindrical bosses, and a plurality of flexible rubber elements fitting over said bosses and suitably secured in position thereon and extending upwardly into the crate and cooperating to space apart the bottles to prevent direct contact therebetween.

HENRY V. BOWMAN.
